UNITED STATES PATENT OFFICE.

WILLIAM SHAKESPEARE, JR., AND WALTER E. MARHOFF, OF KALAMAZOO, MICHIGAN; SAID MARHOFF ASSIGNOR TO SAID SHAKESPEARE.

CLICK MECHANISM FOR FISHING-REELS.

SPECIFICATION forming part of Letters Patent No. 734,972, dated July 28, 1903.

Application filed November 15, 1902. Serial No. 131,565. (No model.)

To all whom it may concern:

Be it known that we, WILLIAM SHAKESPEARE, Jr., and WALTER E. MARHOFF, citizens of the United States, residing at the city of Kalamazoo, in the county of Kalamazoo and State of Michigan, have invented certain new and useful Improvements in Click Mechanism for Fishing-Reels, of which the following is a specification.

This invention relates to improvements in fishing-reels. It relates particularly to improvements in the click mechanism for fishing-reels and is a modification and in some respects an improvement upon the click mechanism for fishing-reels described in our application for Letters Patent filed August 18, 1902, Serial No. 120,020.

The objects of this invention are, first, to provide an improved click mechanism for fishing-reels which is even and easy in its action no matter which way the spool revolves; second, to provide an improved click mechanism for fishing-reels which is economical to produce and which is durable in use because the wearing parts are comparatively heavy.

Further objects will definitely appear in the detailed description to follow.

The objects of this invention are accomplished by the devices and means described in the following specification.

The invention is clearly defined and pointed out in the claims.

A structure embodying the features of this invention is fully illustrated in the accompanying drawings, forming a part of this specification, in which—

Figure 1 is a front elevation view of a structure embodying the features of this invention. Fig. 2 is a detail sectional view taken on a line corresponding to line 2 2 of Figs. 1 and 3, portions being broken away to show the arrangement of the parts. Fig. 3 is a detail sectional view taken on line 2 2 of Fig. 2. Fig. 4 is a detail sectional view taken on line 4 4 of Fig. 2, showing the manner of supporting the thumb-button D. Fig. 5 is a detail sectional view taken on a line corresponding to line 5 5 of Fig. 6. Fig. 6 is a detail sectional view taken on a line corresponding to line 6 6

of Fig. 5. Fig. 7 is a detail sectional view of a modified structure, taken on a line corresponding to the view shown, Fig. 2.

In the drawings the sectional views are taken looking in the direction of the little arrows at the ends of the section-lines, and similar letters of reference refer to similar parts throughout the several views.

Referring to the drawings, A A' represent the heads of the frame. These are secured together in the proper relation by suitable pillars A" in any preferred form. The spool B, which is provided with suitable bearing-pivots B', is housed and supported by this frame.

Our improved click mechanism is housed on the frame-head A. It consists of a lever C, supported on the pivot a. This lever C is preferably stamped from sheet metal and is substantially V-shaped. It is controlled by the button D, which is pivotally secured in position by the stud D', so that its edge projects beyond the periphery of the frame-head. The periphery of the button D is suitably milled for convenience in manipulation. The button D is formed with a lug or projecting point n', adapted to engage the lever and also to engage the notch n" in the lever to lock the same. A notch n is formed in the button and serves as a stop to limit the movement of the parts in operating the same.

Pivotaly supported on the inner end of the lever C is a click or detent C', adapted to engage the click-pinion B" on the spool. Tension is applied to the lever C by a wire spring c, which is fulcrumed about the pivot a. One end of the spring engages the pin a' on the frame-head A and the other rests on the click or detent C', a suitable groove or kerf being formed therein to retain the spring in position. By this arrangement the spring serves a double purpose—that of holding the lever C in contact with the adjusting-button and under tension and also holding the click or detent yieldingly in position.

In the modified structure shown in Fig. 7 independent springs are shown. The spring e applies tension to the lever only and a second spring e' is provided for the detent or click C'. The spring e' is secured to and carried by the

lever and the inner end of the spring engages the detent in the same manner as in the preferred construction.

It is apparent that by the manipulation of 5 the thumb-button D the click or detent C' is thrown into or out of engagement with the pinion B'', the adjustable position being indicated by dotted lines in Fig. 2.

Our improved click mechanism for fishing-reels is very economical to produce and durable in use. The only wearing part—the detent C'—may be formed of tool-steel or may be case-hardened or tipped with suitable material, so that it is very durable. It is evident 15 that the parts are readily assembled. The click is under the perfect control of the user.

We have illustrated and described our improved click mechanism for fishing-reels in the form preferred by us. We have illustrated 20 a modification and are aware that it is capable of considerable variation in structural details without departing from our invention.

Having thus described our invention, what 25 we claim as new, and desire to secure by Letters Patent, is—

1. In a click mechanism for fishing-reels, the combination of a suitable frame; a click-pinion; a lever C; a pivot *a* for said lever; a 30 click or detent pivotally supported on said lever; a spring *c* fulcrumed on said pivot secured to said frame and arranged to engage

said click, whereby tension is applied to said lever to hold it yieldingly against the actuating means and said click is held yieldingly in 35 position; an actuating-button D having a lug *n'* adapted to engage said lever; a notch *n''* in said lever to engage said lug *n'*; a notch *n* in said button to engage the end of said lever and serve as stops, all coacting for the purpose 40 specified.

2. In a click mechanism for fishing-reels, the combination of a suitable frame; a click-pinion; a pivotally-supported lever; a pivotally-supported click carried by said lever; a 45 spring arranged to hold said click yieldingly in position and apply tension to said lever; and a thumb-button for controlling said lever.

3. In a click mechanism for fishing-reels, the combination of a suitable frame; a click-pinion; a pivotally-supported lever; a click or detent adapted to engage said pinion carried by said lever; a spring arranged to hold 50 said click yieldingly in position; and apply tension to said lever, for the purpose specified.

In witness whereof we have hereunto set our hands and seals in the presence of two witnesses.

WILLIAM SHAKESPEARE, JR. [L. S.]
